ELEVATOR ROLLER GUIDE SHOE

Clifford Norton, South Orange, N. J., assignor to
Otis Elevator Company, New York, N. Y., a corporation of New Jersey

Application September 10, 1935, Serial No. 39,906

2 Claims. (Cl. 187—95)

This invention relates to guides and especially to guides for the movable bodies of elevator installations.

In the elevator art the elevator car and counterweight are commonly provided with guides for cooperating with the guide rails, whereby the car and counterweight are guided in their movement in the hatchway. In many elevator installations, the guide rails are not perfectly straight and smooth, so that with solid guide shoes there is a tendency for the car to sway as it passes up and down the hatchway, particularly in the case of high speed elevators. Furthermore, when metallic guide shoes are used, considerable noise is developed.

It is the object of this invention to provide a guide which is noiseless in operation and which, when used on the elevator car, provides smooth operation.

20 In carrying out the invention, rubber tired ball bearing rollers in yielding engagement with the guide rail are employed. This invention is particularly applicable to T-shaped guide rails in which the two sides and the face of the stem 25 of the guide rail serve as guiding surfaces. For cooperation with such a guide rail, each guide comprises three rollers, one for each of the three guiding surfaces of the guide rail. Each roller is mounted at one end of a substantially vertical 30 straight lever which is fulcrumed near its center on a guide stand. Near the other end of the lever there is provided a compression spring which rocks the lever about its pivot in a direction to maintain the roller in engagement with the 35 rail, a stop being provided to prevent more than a limited amount of movement of the lever about its pivot in the opposite direction. Such construction results in a very compact guide.

The features and advantages of the invention 40 will become apparent from the specification and appended claims.

The invention will be described as employed for guiding an elevator car in its movement in the hatchway.

45 In the drawings:—

Figure 1 is a schematic view of an elevator installation showing an elevator car equipped with the guiding means of the present invention;

Figure 2 is an enlarged plan view of one of 50 the guides, which is shown in engaging relation with the guide rail;

Figure 3 is an isometric view looking at the front of the guide shown in Figure 2, the guide rail being omitted;

55 Figure 4 is an isometric view looking at the

guide from the rear, and also showing the guide rail; and

Figure 5 is a side view partly in section showing details of construction of one of the side rollers 5 of the guide.

Referring to Figure 1, the numeral 10 designates an elevator car supported by a car sling 11 to which hoisting roping 12 is secured for raising and lowering the car in the hatchway. Guide rails 14 for the car are provided in the hatchway. The guide rails shown are T-shaped and have side surfaces 15 and a face surface 16 for cooperation with guides 17, mounted on the upper and lower cross members of the car sling, to guide the car in its movement in the hatchway. As 15 the guides 17 are of identical construction, only a single guide and the operation thereof will be described in detail.

Referring to Figures 2, 3 and 4, the guide according to the preferred construction comprises 20 a stand 18 having a base 20 which is secured to the car sling 11 as by bolts through holes 21 in the base. A block 25 extends vertically from the base and is provided with a groove 26 into which the guide rail extends. At the top of the block 25 are formed lugs 22, 23 and 24, lugs 22 and 23 extending oppositely from the block parallel to the base of the guide rail and lug 24 extending back from the block in line with the guide rail stem. Each of these lugs is connected by a rib 29 to the base. Each lug is provided with an aperture to receive a bolt 30 which forms a pivotal support for a straight lever 28. Each of these levers in turn carries a guide roller at one 30 end for cooperating with the guide rail. The 35 construction of only one lever and guide roller will be described in detail as the construction of the others is substantially the same.

Referring to the lever supported by lug 23, the lever extends substantially parallel with the guide 40 rail and is pivoted by bolt 30 substantially midway its ends. The bolt is journalled in the aperture in the lug and the lever is secured by a nut 31 against a shoulder formed on the bolt. Referring also to Figure 5, the guide roller 32, carried by the lever, is in the form of a disc wheel 45 having a hub 42 and a rim 39. The wheel is provided with a ball bearing 40, which may be packed in grease. An aperture is provided in the hub to receive the bearing. The outer race of the bearing is secured in place as by peening the hub over the race at a plurality of points 43. Bolt 33 50 clamps the inner race of the bearing to the lever, thereby rotatably securing the roller to the end of the lever. On the outside of rim 39 is another 55

rim 44. To distinguish these rims, rim 39 may be termed the inner rim while the other rim 44 may be termed the outer rim. The outer rim is peened over the inner rim at a plurality of points 5 designated 45, thereby securing the outer rim to the wheel. The outer rim is preferably brass plated steel and has a rubber tire 41 vulcanized thereon. This tire has a curved tread for rolling upon the side of the guide rail.

10 The tires for the rollers 32 and 46 which co-operate with the sides of the guide rail are of the same shape but the tire for the roller 48 which cooperates with the face of the guide rail is preferably of V-shaped construction with a flat tread 15 51 of a width less than the width of the face of a the guide rail. The rubber of the tires is of a composition and hardness such that it has the property of resuming its normal shape after having been under compression for either short or 20 long periods of time. Should replacement of the tire be desirable, the outer rim may be forced from the inner rim and replaced by a new outer 25 rim and tire, secured in place by peening over as previously described. The ball bearing also may be replaced in a similar manner.

Each lever is provided at its other end with a spring 37 which acts to rock the lever about its pivot to urge the roller carried thereby into contact with the guide rail. The spring for the lever 30 carried by lug 23 extends between a spring seat formed on the block 25 and a spring seat formed by a screw 35 and nut 53 carried by the lever. Screw 35 is adjustably mounted on a bracket 34 secured as by welding to the end of the lever and is 35 locked in adjusted position as by a nut 54. Nut 53 is held on the screw by a pin. The bracket is formed with an arm 55 in which another screw 36 is adjustably mounted. This screw cooperates with the end of a boss 38 formed on rib 29 to limit 40 the amount of movement of the lever in a direction about its pivot opposite to that in which it is urged by spring 37. Screw 36 is locked in adjusted position as by nut 56.

The arrangement of the spring 37 and the limit 45 stop for the lever carried by lug 24 is the same as that described above. In the case of the lever carried by lug 24, however, the adjusting screw 35 for the spring is carried by the same arm of the bracket that carries screw 36.

50 The rollers 32 and 46 are maintained in continuous engagement with the side surfaces 15 of the rail, and the roller 48 is maintained in continuous engagement with the face surface 16 of the rail by their respective biasing springs. Upon travel of the car in the hatchway, the rollers 55 roll along their respective guiding surfaces to guide the car in its movement. In the event that irregularities occur in the proper alignment of the rail, the rollers move relatively to stand 18 to compensate for such irregularities. Assume, for example, that the guide rail is displaced sideways in a direction toward roller 32. When the rollers pass over the point at which the rail is displaced, the arm 28, carrying the roller 32 engaging the 60 side surface 15 which is displaced toward the roller, moves counterclockwise as viewed in Figure 3, compressing the associated spring while the spring associated with the arm carrying roller 46 engaging the opposite side surface 15 acts to move the arm about its pivot whereby roller 46 is maintained in engagement with the rail. When the 65 guide rail is displaced in a direction away from roller 32, the rollers move to compensate for such a displacement with roller 32 being moved by the 70 force of its spring and roller 46 being moved 75

against the force of its spring. In the event that the guide rail is displaced in a direction either toward or away from roller 48, the roller is moved relative to the stand to compensate for such a displacement by or against the force of its 5 spring in a manner as previously described for rollers 32 and 46. Thus, the side rollers 32 and 46 and the face roller 48, being maintained in continuous yielding engagement with the guiding surfaces of the rail, provide quiet and smooth opera- 10 tion.

It is to be noted that upon lateral movement of roller 48 the tread 51 thereof, being of a width less than the width of face surface 16, does not overlap the rail, thereby preventing the tread 15 from being grooved or cut by the sharp edge of the rail.

An irregularity in the guide rail may occur which may require more compensating movement of the rollers than that provided by the roller arms. In such an event a pressure is exerted on the rollers whereby the roller arms are rocked to the limit of their compensating movement, further pressure on the rollers resulting in the compression of the rubber tires of the rollers. 25

In the event that any of the rollers or parts thereof become broken in the operation of the car, the sides of the guide groove 26 cooperate with the guide rail to maintain the car in its proper position until repairs can be effected. It 30 will be understood that the dimensions of groove 26 are such that, in the normal operation of the guide, the sides and face of the groove do not contact the corresponding surfaces of the guide rail. 35

The employment of roller guides renders the application of lubricants such as oil to the guide rails unnecessary. This is of advantage as the expense of lubrication and the possibility of oil or grease coating the hatchway and elevator car are 40 avoided.

What is claimed is:—

1. In an elevator installation in which a guide rail having a flat guide surface on its face and on each of its two sides is provided for a body 45 movable in the elevator hatchway and in which a plurality of guide rollers, one roller for each of said guiding surfaces, is carried by said body, each roller being yieldably maintained in continuous rolling engagement with the guide rail 50 to guide said body in its movement in the hatchway, the construction of said rollers wherein each of them comprises a wheel having a metal rim and a rubber tire vulcanized to said rim, the tires of the rollers for the side guiding surfaces of said 55 rail each having a curved tread and the tire of the roller for the face guiding surface of said rail having a flat tread of a width less than the width of said face guiding surface, and the rubber of each tire being of a composition and hardness such that the tire resumes its normal shape after being subjected to pressure at the same point over an extended period of time. 60

2. In an elevator installation in which a guide rail having a flat guide surface on its face and 65 on each of its two sides is provided for a body movable in the elevator hatchway and in which a plurality of guide rollers, one roller for each of said guiding surfaces, is carried by said body, each roller being yieldably maintained in continuous 70 rolling engagement with the guide rail to guide said body in its movement in the hatchway, the construction of said rollers wherein each of them comprises a wheel having a brass plated steel rim removably secured to said wheel and a 75

rubber tire vulcanized to said rim, the tires of
the rollers for the side guiding surfaces of said
rail each having a curved tread and the tire
of the roller for the face guiding surface of said
5 rail being V-shaped and having a flat tread of a
width less than the width of said face guiding
surface to permit a certain lateral movement of

such tread without the tread overlapping said
face guiding surface, and the rubber of each tire
being of a composition and hardness such that
the tire resumes its normal shape after being sub-
jected to pressure at the same point over an ex- 5
tended period of time.
